CENTRIFUGE CONSTRUCTION

Oscar W. Johnson, Houston, Tex., assignor, by mesne assignments, to Dorr-Oliver Incorporated, Stamford, Conn., a corporation of Delaware

Application February 20, 1956, Serial No. 566,464

4 Claims. (Cl. 233—2)

This invention relates generally to centrifuge machines of the type adapted for the continuous separation and discharge of solid components from a feed material.

Commercial centrifuges are available which are supplied with feed material continuously, as distinguished from batch operation, and which effect continuous centrifugal separation with discharge of an underflow containing heavier solid components. Such continuous machines are disclosed for example in Patents No. 2,525,629, 2,559,453, 2,616,620, and 2,625,321. The machines disclosed in said patents utilize so-called return circuits by means of which a large part of the centrifugally separated underflow is continuously returned into the centrifuge rotor, to thereby increase the amount of material of underflow consistency continuously discharging through the underflow nozzles. When employed in certain commercial processing operations, such machines may be subject to troublesome clogging of the underflow nozzles. Clogging reduces operating capacity, and makes it necessary to shut down the machine for servicing. Troublesome clogging may be experienced even though screening or sizing methods are used on the feed material. With certain types of feeds clogging may be caused by build up of solid material within the centrifuge chamber, with occasional sloughing off of built up fragments. In other instances clogging may be experienced immediately after the machine is placed in operation following a shutdown period, and may be due to a build up of deposits occurring during shutdown, which slough off when the machine is started in operation.

In my copending application Serial No. 544,173, filed December 20, 1955, there is disclosed a centrifuge of the continuous type having a screen positioned within the rotor in such a fashion that centrifugally separated underflow material must pass through the same, before discharging through the underflow nozzles. The particular construction disclosed in said copending application employs a continuous band of foraminous or screen material, which extends about the main separating chamber, and is interposed between the separating chamber and regions in the periphery of the rotor that communicate with the underflow nozzles.

It is an object of the present invention to provide another type of screen construction which will perform the functions of the screen disclosed in said copending application, and which will afford certain advantages, including ease of servicing.

Another object of the invention is to provide a centrifuge of the above character having screens that are incorporated in conjunction with the nozzle assemblies, and which can be removed from the exterior of the machine, together with the nozzles.

Additional objects and features of the present invention will appear from the following description in which the preferred embodiment has been set forth in detail in conjunction with the accompanying drawing.

Referring to the drawing:

Figure 1 is a side elevational view in one-half section

2

illustrating a centrifuge incorporating the present invention.

Figure 2 is a cross-sectional view on an enlarged scale taken along the lines 2—2 of Figure 1.

Figure 3 is a side elevational view in section illustrating the nozzle and screen assembly shown in Figure 2.

Figure 4 is a view like Figure 3, but showing another embodiment.

The centrifuge illustrated in the drawing consists of a rotor 10 carried by the vertical shaft 11. The housing 12 encloses the rotor and is provided with means for collecting the underflow and overflow material, as will be presently explained. The upper and lower main sections 10a and 10b of the rotor are secured together by 15 suitable means such as the clamping ring 13. The outer peripheral portion 14 of the rotor carries a plurality of underflow discharge nozzles 16. The number of nozzles may vary in different instances, depending upon such factors as the size of the machine, the capacity of operation, 20 and the type of material upon which separation is being made.

Underflow material discharging from the nozzles 16 is collected in the housing volute 17. This volute is connected with external piping whereby a large amount of 25 the underflow material is continuously returned back into the lower impeller portion 18 of the rotor, through the upwardly directed control valve 19. Such an arrangement is disclosed for example in Patent 2,616,620. The impeller portion 18 of the rotor serves to deliver the 30 underflow material outwardly through the passages 20, and through the annular orifice 21 into the separating chamber 22.

The separating chamber is provided with spaced separating disks 23, and with suitable provision for the discharge 35 of a centrifugally separated overflow, such as the overflow discharge lip 24. The overflow is collected in the volute 26, for removal.

The underflow discharge nozzles 16 receive material from regions 27, which are located outwardly with respect to the main separating chamber. In the embodiment 40 illustrated in Figure 2, the regions 27 are hopper shaped, and are separated and contoured by the so-called hopper blocks 28. These hopper blocks can be made of suitable material, such as fabric reinforced molded plastic, and 45 are each held in place by a suitable means such as a screw 29. The annular rotor space 31, which accommodates the block 28, and which provides the hopper shaped regions 27 between the blocks, may be formed as an outward extension from the main centrifuge chamber.

Referring to Figure 3, each of the nozzles 16 carries a screen 32, whereby underflow material must pass through the screen before passing through the nozzle orifice. The nozzle in this instance incorporates features disclosed 55 and claimed in Patent 2,695,748. Thus the nozzle includes a body 33 which is annular in section (e.g. cylindrical) and is dimensioned to fit within the bore 34 formed in the peripheral wall of the rotor. Suitable sealing means such as the resilient O-ring 36, forms a seal 60 between the body and the rotor. A lug 37 on the body is adapted to interlock with a corresponding recess provided in the rotor wall, whereby when the body is rotated through substantially 180°, it can be retracted from the rotor. The fluid passage 38 in the body 33 delivers material to the nozzle orifice 39, which can be formed in a 65 wear-resisting insert 41. The periphery of the rotor is shown cut away at 42, to accommodate the discharging material.

The screen 32 is attached to the inner end of the body 70 33. It consists in this instance of a cylinder 43 formed of metal or some other suitable rigid material having sufficient strength, and provided with a plurality of longi-

tudinally extending slots 44. The inner end is provided with a removable closure 46. The slotted cylinder 43 is securely attached to the inner end of the body 33, as by brazing or welding.

Assuming that all of the nozzles are constructed as described above, it will be apparent that the underflow material must pass through the screens before being discharged through the nozzle orifices. The width of the slots 44 is such as to prevent oversized material from reaching the nozzles 39. In other words the width of the slots is less than the orifice diameter, thus preventing the nozzles from receiving material which causes clogging.

After an extended period of operation sufficient solid material may have accumulated upon the screens to reduce the capacity of the machine. When this occurs the machine can be shut down for a sufficient period of time to permit one to remove the nozzles, and to clean the screens of accumulated solids. Cleaning is facilitated by removing the closure 46.

As will be evident from Figure 2, the screens do not extend into the main centrifuge chamber 22. Therefore they are immersed only in material of underflow consistency maintained within the hopper-like regions 27 by virtue of centrifugal separation and the continuous return of underflow material. Thus the screens do not interfere with proper separating action, and they do not cause any bypassing of material from the main separating chamber through the underflow nozzles.

As shown in Figure 4, the cylindrical screen 48 can be provided with a plurality of holes or perforations, instead of the slots 44. Also this screen is provided with a permanent end closure 49, and it is removably seated upon the collar 51 provided on the body 33. Suitable attaching means, such as the pin 52 and the L-shaped slot 53, facilitate attachment and removal of the screen. In connection with this embodiment it will be noted that the end closure 49 is conical shaped. This facilitates the deflection of fluid material to which the end of the screen may be subjected, and tends to minimize accumulation of solids upon the end surface during operation.

I claim:

1. In a centrifuge of the continuous type, a rotor having means for supplying a feed material to the separating chamber of the same and means for discharging a centrifugally separated overflow, the rotor also having a main separating chamber adapted to receive the feed material, a plurality of underflow nozzle assemblies removably seated in circumferentially spaced bores in the peripheral annular wall of the rotor, each nozzle assembly including a hollow body having only its outer portion seated in one of said bores for ready removal of the assembly from the rotor, the inner portions of said nozzle bodies being free from support by the rotor and being located in regions within the rotor generally surrounding the main separating chamber and which contain only material of underflow discharge consistency, and a screen carried by the inner portion of each body through which underflow material is caused to flow in discharging from said regions through said nozzle assemblies, said screens being disposed entirely within said regions and formed for direct flow of underflow material therethrough.

2. A centrifuge as in claim 1 together with means within the rotor forming regions that are hopper-like, and in which the screens of said nozzle assemblies are disposed completely within such hopper-like regions.

3. In a centrifuge of the continuous type, a rotor having means for supplying a feed material to the separating chamber of the same and also means for discharging centrifugally separated overflow and underflow fractions, a plurality of underflow discharge nozzle assemblies, each assembly comprising a hollow elongated body, circumferentially spaced bores formed in an annular peripheral wall of the rotor adapted to accommodate said nozzle bodies, means for releasably locking only the outer end portion of each of said nozzle bodies to said annular wall with the inner portions of the body face of separate support, a plurality of screens mounted upon the inner portions of the nozzle bodies, the interior of the rotor being formed to provide a main separating chamber receiving feed material and hopper-like underflow receiving regions extending outwardly from the main separating chamber to said bores and generally embracing the separating chamber, the material maintained within said regions being of underflow discharge consistency, said screens being disposed completely within said regions and formed for direct flow of underflow material therethrough, said locking means when released permitting ready removal of the nozzle assemblies from the rotor and means for continuously returning underflow material back into the outer part of the main separating chamber.

4. An underflow nozzle construction for a centrifuge of the continuous type wherein a feed material is supplied continuously to the separating chamber of a rotor for centrifugal separation and in which the rotor has provision for continuous discharge of overflow and underflow fractions, the underflow fraction being continuously discharged from a zone of substantial depth of underflow material of discharge consistency maintained in the outer peripheral portion of the rotor chamber, there being circumferentially spaced openings in the rotor adapted to receive underflow discharge nozzles; said underflow nozzle construction comprising a body forming a flow passage for underflow discharge material, the body having a discharge nozzle at its outer end and a screen carried by the inner portion of the body, the outer end portion only of the body being attached to the outer peripheral wall of the rotor for ready removal therefrom, the inner portion of the body being free from supports, said screen forming means to pass underflow discharge material entering said passage from the interior of the rotor without substantial change in the direction of flow and to prevent delivery of oversize fragments to the nozzle, said screen being disposed completely within said zone of discharge consistency.
